US00D810832S

(12) **United States Design Patent** (10) Patent No.: **US D810,832 S**
(45) Date of Patent: **** Feb. 20, 2018**

(54) **GAME CONSOLE SUPPORT**

(71) Applicant: **Zihao Peng**, Guangdong (CN)

(72) Inventor: **Zihao Peng**, Guangdong (CN)

(73) Assignee: **Shenzhen Jinhe Global Electronics Co., Ltd.**, Xixiang Sub-dist., Baoan Dist., Shenzhen, Guangdong (CN)

(**) Term: **15 Years**

(21) Appl. No.: **29/590,142**

(22) Filed: **Jan. 6, 2017**

(51) LOC (11) Cl. **21-01**

(52) U.S. Cl.

USPC **D21/333; D14/434; D14/432**

(58) **Field of Classification Search**

USPC .... D14/217, 209.1, 432-434, 447, 188, 356, D14/251; D21/332, 333, 324; D13/107, D13/108, 146; 361/679.4, 361/679.31-679.33, 679.55; 455/347-357; 273/148 B; 463/1, 29-35, 463/46, 47

CPC **A47B 21/04; A47B 2097/005; A47B 2023/049**

See application file for complete search history.
